UNITED STATES PATENT OFFICE.

HENRY COLE WILLMOTT, OF SOUTH WOODFORD, ENGLAND.

SHEATH FOR SCISSORS OR THE LIKE.

SPECIFICATION forming part of Letters Patent No. 723,109, dated March 17, 1903.

Application filed September 23, 1902. Serial No. 124,526. (No model.)

To all whom it may concern:

Be it known that I, HENRY COLE WILLMOTT, a citizen of the United Kingdom of Great Britain and Ireland, residing at Gothic 5 Villa, Maybank Road, South Woodford, county of Essex, England, have invented certain new and useful Improvements in Sheaths for Scissors or the Like, of which the following is a specification, such as will enable others skilled in the art to which it appertains to make and use the same.

My invention relates to scissors and the like cutting instruments; and it consists in attaching to the same a sheath formed as a hollow 15 case, preferably made of metal, which when the scissors are not in use may be placed over their blades, protecting them from injury and allowing them to be freely handled or carried in the pocket without danger. The sheath is 20 attached to the scissors by a pivot, screw, or the like in such a manner as to be capable of being folded away or back from the blades when the scissors are required for use. The pivot or screw may be an additional one or 25 may be the same as that by which the two halves of the scissors are held together. By preference the sheath is made with extended ends or lugs through which the rivet or screw is fixed or fitted. The sheath closes onto the 30 scissors from one edge—that is to say, over the back of one of the blades and the front of the other when the scissors are closed—and it is preferably large enough to completely cover the whole of the blades, and one edge of the 35 said sheath is open to allow it to pass over the blades of the scissors. The two sides of the sheath are slightly curved, so as to spring onto and over the blades, keeping the sheath in position and the blades closed when the 40 scissors are not required for use.

Further objects and the advantages of my invention will appear in the following description.

In the drawings, Figure 1 represents a pair 45 of scissors fitted with my invention, the rivet or pivot of the sheath being fitted to one of the shanks between the bow and the blade. Fig. 2 is a view of a similar pair of scissors to those shown in Fig. 1, but shows the same

slightly open and with the sheath removed 50 from the blades. The sheath is also shown by line and dot bent or turned back close to one of the bows of the scissors. Fig. 3 is a longitudinal section on the line 1 1 in Fig. 5 of the sheath. Fig. 4 is a cross-section on the 55 line 2 2 of the sheath shown in Fig. 3. Fig. 5 is an edge view of the sheath shown in the foregoing figures as viewed from the open side of the same.

a is the sheath, pivoted at *b* to the scissors 60 *c*. *a'* (shown in Figs. 3, 4, and 5) is the top of the sheath, which covers or protects the points of the blades. In Fig. 5 the two sides *a²* *a³* of the sheath are shown curved, by which means the slight springy action above referred to is 65 obtained.

It will be seen that the invention is of simple construction and is a thoroughly-effective protector or sheath for the blades. It is not necessary to remove the sheath from the 70 blades by the fingers when the scissors are required for use, because the action of opening the scissors by the bows in the usual manner also pushes back the sheath sufficiently far to disengage the blades therefrom. 75

I do not confine myself to any particular shape or size of sheath, and the same may be ornamental, plain, or be used for advertisement purposes.

Various changes in the form, proportion, 80 and minor details of construction may be resorted to without departing from the principle or sacrificing any of the advantages of this invention.

Having described my invention, what I 85 claim, and desire to secure by Letters Patent, is—

1. A sheath for scissors and the like cutting instruments consisting of a hollow case, of resilient sheet metal one edge of which is 90 open to fit over the blades of the scissors, said sheath being attached to the scissors by a suitable pivot-joint, and the sheath being adapted to entirely inclose the blades of the scissors when in the closed position, substantially as 95 shown and described.

2. The herein-described sheath for scissors and the like cutting instruments, said sheath

being attached to said scissors by a rivet, pivot or screw upon which rivet, pivot or screw the sheath may be turned back, which sheath is formed as a hollow case, one edge of which is 5 open to allow the said sheath to pass onto the blades of the said scissors, which blades are held together and prevented from opening by the spring-like formation or nature of the

sides of the said sheath, substantially as specified.

In witness whereof I have hereunto set my hand in presence of two witnesses.

HENRY COLE WILLMOTT.
